LOCOMOTIVE STRUCTURE

James C. Travilla, Jr., Philadelphia, Pa., assignor
to Granite Steel Castings Corporation, Granite
City, Ill., a corporation of Delaware

Application January 9, 1933, Serial No. 650,836

5 Claims. (Cl. 105—44)

This invention relates to railway rolling stock and consists particularly in a novel cylinder saddle structure for locomotives.

The present tendency in locomotive construction is to form the cylinder saddle, including the main cylinders, steam chests, exhaust passages and central smoke box support integrally, all the parts being included in a single casting, or in a pair of sections bolted together at the middle.

10 The saddle may be formed integral with the main underframe, or provided with bolting surfaces for attachment to underframe longitudinals. In most cases the exhaust passages extend diagonally from the ends of the steam chests through the corners of the hollow smoke box support and merge in an exhaust outlet in the center of the support and extending upwardly into the smoke box. Thus the passages merge with and, during operation, impart their heat directly to only

15 small portions of the support webs.

Accordingly, the walls of the central part of the saddle which are spaced from the cylinders, steam chests, and exhaust passages, remain comparatively cold and tend to resist expansion of the exhaust passages under the influence of the hot steam. This condition may result in the cracking of the saddle walls and particularly the front and rear walls of the smoke box support.

Also in previous forms substantial parts of the 20 exhaust passages are located within the smoke box support and cannot be readily reached for inspection and repair purposes and the converging passages constrict the space between the cylinders and frame which must be accessible for inspection and repair purposes.

The main object of the present invention is to decrease or eliminate the undesirable differential thermal stresses referred to above which may result in damage to the casting.

40 Another object is to decrease the amount of metal used in the cylinder saddle while at the same time strengthening the tie between the chest passages and the smoke box support by utilizing the exhaust passages as parts of the smoke box support walls.

Another object is to simplify the construction of the cylinder saddle and also facilitate access to the inner surfaces of the cylinders and chests and to the exhaust passages for the purpose of inspection and repairs.

These objects and others are attained substantially by the structures illustrated in the accompanying drawings, in which—

Figure 1 is in part a top view of a cylinder saddle structure illustrating the invention and in

part a horizontal section taken on the broken line 1—1 of Figure 2.

Figure 2 is a vertical transverse sectional view taken on the line 2—2 of Figure 1.

Figures 3 and 4 are vertical longitudinal sections taken on the corresponding section lines of Figure 2.

Figure 5 is a view corresponding to Figure 1 but illustrating a modification.

Figures 6 and 7 are vertical longitudinal sections taken on the corresponding section lines of Figure 5.

The cylinder saddle is shown cast integral with the locomotive main underframe and front deck structure, indicated generally at A and B, and including top and bottom horizontal webs 6 and 14, outer side walls 15, and inner vertical walls 16 forming a box section backbone member extending through the saddle and front deck structure. Cylinders C are located in the usual position at the sides of the underframe, and steam chests D are supported above the cylinders by means of webs E forming connecting steam passages between the cylinders and chests.

The smoke box support is substantially of box section, including inclined longitudinal walls 1 merging at the bottom with the cylinders C and with flanges 2 at the top for seating the smoke box. Exhaust passages 3 extend directly inwardly from the ends of the steam chests at right angles to the walls 1 and near the longitudinal center of the saddle curve sharply inwardly and upwardly, as at 4, and merge in exhaust outlets 5 extending into the smoke box (not shown) and flanged for mounting an exhaust nozzle. The 30 exhaust passages are shown as of rectangular section with the lower walls thereof being in alignment with and merging with the top wall 6 of the underframe.

Extending above the top walls of the exhaust 40 passages and in alignment with the inner walls 17 thereof are webs 7 around the upper edges of which the flanges 2 are continued to form an arcuate smoke box support. Each of the webs 7 forming the upper parts of the smoke box support front and rear walls extends in a continuous vertical plane between the walls 1, while the portions 3 of the exhaust passages, forming the entire lower parts of these front and rear walls, are depressed inwardly near the center. A substantially horizontal web 8 spaced above the top web 6 of the underframe extends between the lower edges of each web 7 and merges with central triangular elements 8a which close the spaces between the curved portions 4 of the passages and 55

form offset continuations of the boiler seating webs 7. Openings 8b facilitate molding and cleaning but are closed in the completed structure by plates P welded in place.

5 In Figures 5 to 7, the underframe is shown as composed of spaced longitudinals F with webs 20 and 21 forming a box-shaped base of the saddle. The saddle construction is in general similar to that just described except that the exhaust passages 9 extend diagonally inwardly from the steam chests through the ends of the inclined longitudinal walls 10 of the smoke box support and then transversely along the front and rear walls thereof, the flanged smoke box seating webs 11 being in alignment with the outer walls 18 of the exhaust passages instead of the inner walls thereof as in the previous form. In this, as well as the previous form, the lower edges of the webs 11 merge with the upper walls of passages 9 and 20 with the horizontal web 12, no other tie being provided between the sharply curving portions 13.

It will be seen that in each of the forms continuous strips of the front and rear walls of the smoke box support from side to side are entirely replaced by the main exhaust passages. This substantially decreases the amount of metal used and, accordingly, the weight of the structure. Since the exhaust passages are coextensive with considerable parts of the smoke box wall, the tie 30 between the chests and smoke box support is strengthened over that in previous forms in which the passages extend diagonally through the support walls. Also substitution of the passages for large portions of the front and rear 35 walls of the smoke box support substantially lessens differential thermal stresses between the support walls and the exhaust passages referred to above as being present in cast metal saddles of this general type in which different portions of 40 the saddle are subjected to different temperatures by exposure to the exhaust steam and atmospheric temperatures.

Furthermore, the wide separation of the exhaust passages facilitates access to the inner surfaces of the cylinders and steam chests, and also larger portions of the passages themselves are more readily accessible than has previously been the case.

Obviously the invention is not limited to the 50 details of the structure as illustrated but may be modified in various respects as will occur to those skilled in the art to which the invention pertains, and the exclusive use of all such modifications as come within the scope of the appended claims is contemplated.

What is claimed is:

1. A locomotive cylinder saddle integral struc-

ture including front and back walls, steam chest elements adjacent the ends of said walls, and exhaust passages extending from said elements along both of said walls for substantial distances and then merging in an exhaust outlet, said 5 passages forming continuous strips of said walls from end to end thereof.

2. A locomotive underframe integral cast structure comprising a main frame part, steam chest elements at the sides of said part, main exhaust 10 passages extending directly inwardly from said elements and merging with the top wall of said part and then curving longitudinally and merging with each other in a central exhaust outlet, and a boiler seating flanged web extending along 15 portions of said passages and above the same, the normal walls of said passages forming substantially the entire lower part of a boiler support wall from side to side and above said main frame member.

3. A locomotive cylinder saddle and boiler support integral cast structure comprising a base part, steam chest elements at the sides of said part, main exhaust passages extending directly 20 inwardly from said elements and then curving longitudinally and merging and thence extending upwardly in a central exhaust outlet, and a boiler seating flanged web extending along portions of said passages, the normal walls of said 25 portions of said passages forming substantially the entire lower part of a boiler support wall above said base member, said web including an upwardly disposed portion and a portion at the 30 lower edge thereof disposed at an angle thereto and closing the space between the longitudinally 35 curved central portions of said passages.

4. A locomotive cylinder saddle integral structure including a base part, steam chest elements at the sides thereof, a boiler support including longitudinal and transverse walls, and main exhaust passages extending inwardly from 40 said elements and having longitudinally curved portions merging in an exhaust outlet, a section of said transverse wall being coextensive with a 45 wall of each of said passages from side to side of the structure and said section being indented to conform with the curved portions of said passages.

5. A locomotive underframe structure including a bracing wall and steam passages extending 50 towards each other along one side of said wall and then curving inwardly through said wall and merging, there being a recess in said wall between the inwardly curving parts of said 55 passages.

CERTIFICATE OF CORRECTION.

Patent No. 2,065,632.

December 29, 1936

JAMES C. TRAVILLA, JR.

It is hereby certified that the name of the assignee in the above numbered patent was erroneously described and specified as "Granite Steel Castings Corporation" whereas said name should have been described and specified as General Steel Castings Corporation, of Granite City, Illinois, a corporation of Delaware, as shown by the records of assignments in this office; and that the said Letters Patent should be read with this correction therein that the same may conform to the record of the case in the Patent Office.

Signed and sealed this 2nd day of March, A. D. 1937.
